UNITED STATES PATENT OFFICE.

PAUL WALKER, OF CHICAGO, ILLINOIS, ASSIGNOR TO CHICAGO CARTON COMPANY, OF CHICAGO, ILLINOIS, A CORPORATION OF ILLINOIS.

FOLDING PAPER BOX.

1,411,678.

Specification of Letters Patent.

Patented Apr. 4, 1922.

Application filed August 10, 1917, Serial No. 185,427. Renewed June 15, 1921. Serial No. 477,863.

To all whom it may concern:

Be it known that I, PAUL WALKER, a citizen of the United States, and a resident of Chicago, county of Cook, and State of Illinois, have invented certain new and useful Improvements in Folding Paper Boxes, of which the following is a specification.

The invention relates to folding paper boxes and seeks to provide improved means 10 for connecting the side and end walls or panels thereof.

The invention consists in the features of improvement hereinafter set forth, illustrated in different preferred forms in the 15 accompanying drawings and more particularly pointed out in the appended claims.

In the drawings, Figure 1 is a plan view of a blank for forming a folding box embodying the present improvements. Fig. 2 20 is a cross section of the box made from a blank shown in Fig. 1, with the cover portions in folded position. Fig. 3 is a similar view with the cover portions in display position. Fig. 4 is a detail section on the line 4—4 of Fig. 3. Fig. 5 is a blank for 25 forming another style of box embodying certain features of the present invention. Fig. 6 is a perspective view of a box made from the blank shown in Fig. 5.

The form shown in Figs. 1, 2, 3 and 4 30 comprises a bottom panel *a*, side panels *b* integrally hinged thereto along side scores *l* and end panels *c* integrally hinged to the main panel *a* along end scores *2*. The side panels *b* form the front and rear walls of the 35 box and are provided at their ends with extensions or wings *d* integrally hinged thereto along scores *3*.

These wings are of substantially the same 40 height as the end panels *c* or are preferably very slightly narrower than the end panels and are arranged against the inner faces of the end panels when the box is set up. The end panels are provided with extensions or 45 flaps *f* connected to the outer edges thereof along the scores *4* and which are adapted to fold inwardly and overlap the wings *d*.

To securely connect the parts and form 50 stiff end walls, the main panel *a* and preferably the scores *2* at its ends, are provided with one or more slits *5* and the locking panels *f* are provided at their edges with tongues *6* arranged to engage said slits. In the form shown, there are two slits at each 55 end of the main panel *a* and each of the

locking flaps are provided with two tongues 6. Preferably, the slits are straight and quite narrow, being mere cuts in the paper stock formed at the inner parts of the scores 2. The width of each locking flap and one 60 of its tongues from the outer edge of the tongue to the score 4 is substantially equal to the height of the box or to the width of the end panel *c* plus the thickness of the box material. Furthermore, the tongues 65 are in line with the flaps and are substantially rigid therewith. That is to say, there are no scored portions between the tongues and the main body of the locking flap.

In setting up the box, the side panels or 70 front and rear walls *b*, and the end panels *c* are folded upwardly upon the scores 1 and 2 and the wings *d* are folded inwardly against the inner faces of the end panels. The locking flaps are then folded inwardly 75 about the scores 4 and, as each flap is moved from the position shown in dotted lines in Fig. 4 to the position shown in full lines thereof, the tongues *6* snap into the slits *5* in the scores 2 so that the wings *d* of the side 80 panels are snugly gripped between the end panels and the locking flaps. As the flap is swung about its hinged edge from the position shown in dotted lines in Fig. 4 to that shown in full lines, the rigid tongues on its 85 edge will press down the edge portion of the box bottom *a* and engage and project slightly into the narrow cuts or slits *5* which securely grip the tongues. The construction forms a very secure lock between the sides 90 and ends of the box and also forms a very strong end wall construction.

The box shown is provided with a combined cover and display surface *e* which is 95 integral with and hinged to the rear wall *b* along the score 7. It is provided at its edges with wings or brackets *g* hinged thereto along the scores 8. These brackets are provided with triangular portions *9* cut out of the adjacent wings *d* and are connected 1. thereto along scores 10. These triangular portions *9* are provided with tongues *11* which are arranged to engage slots *12* formed in the scores 4 at the upper edges of the end walls or panels *a*.

The front side panel *b* is provided with an integral display portion or panel *h* hinged thereto along a score 13 and provided with integral end wings 14 hinged thereto along scores 15. In the closed position of the box, 11

the brackets *g* are arranged against the inner faces of the ends of the box with the portions 9 thereof against the rear wall, as shown in Fig. 2. Also, in this position, the 5 front display panel *h* preferably overlaps the display cover *e* and the wings 14 extend downwardly between the brackets *g* and the end walls of the box. When the box is set up for display, the panel *h* is folded over 10 against the outer face of the front walls *b* with the wings 14 tucked into the folded ends. The tongues 11 on the triangular bracket portions 9 are engaged with the slots 12 and thus hold the combined cover and display surface *e* in an upwardly and rearwardly inclined position, as shown in Fig. 3.

The improved means for locking the sides and ends may be applied to different types of boxes and to box lids. In the form shown 20 in Figs. 5 and 6 the main panel *a* or the bottom of the box, the side and end panels *b* and *c* and the connected parts are substantially similar to those already described except that the box is narrower and the locking flaps *f* are each provided with but a 25 single tongue 6'. The rounded form of this tongue facilitates the folding or setting up of the ends.

In this form a cover is provided and comprises a main panel *a'* hinged to the edge of the wall or side panel *b* along a score 16. This main panel is slightly larger than the main panel *a'* of the box body and is provided with one side panel *b'* and two end 35 panels *c'* which are hinged thereto along side and end scores 1 and 2. Like the corresponding portions of the box body, the side panel *b'* is provided with wings *d'* hinged to its ends by the scored portions 3 40 and the end panels *c'* are provided with locking flaps *f'* hinged thereto by the scored portions 4 and having substantially rigid locking tongues 6' in alignment therewith. The wings *d'* of the cover are preferably 45 slightly longer than the wings *d* of the box body and slits 5 and cooperating tongues 6' are preferably offset from central position toward the rear edge of the cover. The parts of the box body and cover are set up

as already described, and the construction 50 provides a folding box and hinged cover having overlapping sides and ends which can be readily set up and is of strong construction.

It is obvious that changes may be made in 55 the details set forth without departure from the essentials of the invention as defined in the claims.

I claim as my invention:—

1. In a folding paper box, a main panel 60 having a slit at its end, side and end panels hinged thereto, an inturned end wing hinged to said side panel and arranged against the inner face of said end panel, at least a portion of said wing having substantially the 65 same height as said end panel, and an inwardly folding locking flap hinged to said end panel and having a substantially rigid tongue at its free end, said flap and tongue having a combined width substantially the 70 same as the height of said end panel, said tongue being adapted to snap into said slit as said flap is swung into position about its hinged edge, and said tongue, in operative 75 position, being substantially perpendicular to said main panel, whereby said end wing is securely gripped between said end panel and said locking flap, substantially as described.

2. A folding box portion having a main 80 panel, side and end panels integrally hinged thereto, there being a locking slot at the fold between said main and end panels, and an inwardly folding flap integrally hinged at one edge to said end panel and having a 85 tongue at its opposite edge, said flap and tongue being substantially rigid and having a combined width substantially equal to the height of the box portion, whereby, as said flap is swung to position above its hinged edge, said tongue is adapted to snap into said slot and extend therethrough substantially at right angles to said main panel, said side panel having an inturned end wing 90 disposed between said end panel and said folding flap and adapted to engage the fold between the same.

PAUL WALKER.
